UNITED STATES PATENT OFFICE

CLARENCE I. LANDER, OF SWAMPSOFT, MASSACHUSETTS, ASSIGNOR TO UNITED SHOE
MACHINERY CORPORATION, OF PATERSON, NEW JERSEY, A CORPORATION OF NEW
JERSEY

LAST

Application filed August 9, 1927. Serial No. 211,823.

This invention relates to the art of making shoes and particularly to lasts.

It is desirable, in the manufacture of shoes such as women's light and stylish shoes made by welt and McKay methods in imitation of turn shoes as well as in turn shoes themselves, to provide a close edge about the forepart and shank, that is, to bring the projecting portion of the sole, or the sole and welt in 10 welt shoes, into close relation to the upper. This is particularly important in welt shoes in order that the outsole stitches may be hidden and is peculiarly difficult in welt work because of the bulky character of the inseam, 15 that is, the inseam stitches and the stitch holding portions of the welt, upper and insole, in the trimming of which seam sufficient material must be left to afford adequate anchorage for the stitches.

20 In leveling the foreparts of welt shoes upon lasts of usual construction, the bottoms of which have a convexity or camber, the tend-

20 In leveling the foreparts of welt shoes upon lasts of usual construction, the bottoms of which have a convexity or camber, the tendency of the leveling pressure is to force the material of the insole outwardly. This tendency causes not only loosening of the lasting tension of the upper but also is directly opposed to the formation of a close edge, since outward movement of the inseam, due to the leveling pressure thereon, tends to open the
25 crease between the upper and the sole.
30

Moreover, the bulk of the inseam in proportion to the bottoming materials, particularly in light shoes, is such that the leveling pressure is taken mainly by the inseam and adequate pressure cannot be obtained on the marginal portion of the shoe bottom to produce the desired shaping effects, including a close edge.

Objects of this invention are to provide a last by the use of which in the leveling operation, the above described difficulties may be overcome.

With these objects in view, features of the invention consist in a last the bottom of which has, at the margin thereof, a shallow groove or indented area sub-adjacent to the location of the inseam. The illustrated groove is deepest along the line of the inseam and extends to the extreme edge of the last bottom, becoming shallower as the edge is approached

so that the margin of the last bottom has a downward and inward inclination. As illustrated, the portion of the last bottom inside the grooved or indented margin is unchanged and affords the usual support for the 55 central portion of the insole.

In the drawing,

Fig. 1 is a perspective view of a last embodying the present invention;

Fig. 2 is a transverse section showing the 60 forepart of a shoe made on the last of Fig. 1;

Fig. 3 is a transverse section through the shank of a shoe made on the last of Fig. 1; and

Fig. 4 is a transverse section through a shoe made on a last having at the shank the structure shown in the forepart of Fig. 1 and showing the operation of a leveling tool upon the shoe. 65

In the last of Fig. 1 the body portion 10 and the heel-seat portion, including the heel plate 12, are of usual construction. The bottom of the forepart is formed with a shallow peripheral groove 14 extending around the forepart from the ball line to the ball line. The groove 14 extends to the extreme peripheral edge 16 of the last bottom and is of sufficient width to underlie the region of the inseam 18 of a shoe (Fig. 2), the central portion of the forepart being of usual forma- 70
75
80

portion of the forepart being of usual formation having a transverse and longitudinal camber or convexity. The depth of the groove 14 is slight but sufficient to relieve the pressure of a leveling instrument on the inseam 18 and to concentrate the pressure at the peripheral edge 16 of the last bottom upon the edge of the insole 20, the overlasted upper 22, the welt 24 and the margin of the outsole 26 to force them closely together and close the crease 28 between the upper and welt, or margin of the sole if the shoe has no welt. The formation of the groove 14 provides on the margin of the last bottom a surface 30 directed inwardly and toward the body of the last against which the shoe bottoming materials outside the inseam 18 are pressed and by reason of which the leveling pressure, which is applied perpendicularly to the plane of the shoe bottom, is given an inwardly directed component which causes the inseam to

be displaced inwardly of the shoe, with a consequent tendency to tighten the lasted upper over the last and to close the welt crease 28.

5 The groove 14 may, as illustrated in Fig. 4, extend along the shank as well as about the forepart, the groove in that case extending about the peripheral margin of the last bottom from breast line to breast line. The inner edge of the groove 14 merges into the central cambered surface of the last bottom without any perceptible line of demarcation. The application of an obliquely arranged leveling instrument 32 to the shank portion 10 of a shoe on the last illustrated in Fig. 4 will, by its pressure applied downwardly to the margin of the sole, not only close the welt crease but will, by reason of the grooved surface of the last, tend to force the inseam inwardly. At the same time, the groove 15 relieves the pressure upon the inseam so that the inseam does not offer objectionable resistance to the action of the roll.

Under some conditions, however, it is desirable to have the groove extend about the forepart only and at the shank to provide a recess 34 with outer walls 36 extending heightwise of the last, the recess extending entirely across the shank portion of the last 20 and having a width sufficient to receive the shank portion of the insole, as illustrated in Figs. 1 and 3. The depth of the recess 34 may be equal to the thickness of the insole or may be less than or greater than the insole 25 thickness. This form of the shank portion of the last enables the leveling pressure to be applied to the outsole, welt and upper between the leveling instrument and the rigid surface of the last outside the recessed portion of the shank. Thus, the last provides a 30 firmer support for the upper than is afforded by the margin of the insole against which the leveling pressure would be applied if the last were of the usual construction. The result is a close shank which will 35 remain close during the wear of the shoe.

The last of the present invention provides a convenient and effective means for making from the last a complete and accurate pattern for the insole to be used on the particular last. To make a pattern from the last it is only necessary to cover the last bottom with a piece of paper and to press the paper against the last bottom. This 40 results in the formation of a crease in the paper by the sharp edge of the wall 36 of the groove or recess at the shank and by the sharp edge 16 of the groove about the periphery of the forepart. The edge of the heel 45 plate 12, of course, will serve to form a pattern of the heel-seat portion. By cutting the paper along the crease a pattern for the insole is provided which indicates the proper size and shape of the insole which should 50 be used upon the last. This paper pattern 55

may be used in laying out the usual pattern of metal or cardboard.

The method of leveling a shoe on the illustrated last preferably consists in supporting the extreme edge portion of the insole, which is effected by the edge 16 of the last bottom, relieving the pressure on the inseam, which is effected by the shallow groove 14, and applying pressure progressively about the periphery of the outsole to force the margin of the outsole and welt against the supported edge of the insole, which operation is performed, for example, by the relative traverse of the shoe and a leveling instrument, such as a roll, longitudinally of the shoe bottom 60 while applying pressure heightwise of the last. In this method the inward and heightwise inclination of the margin of the last bottom formed by the outer portion of the groove 14 is utilized to cause the leveling 65 pressure to force inwardly the inseam and consequently to tighten the upper and close the welt crease.

A shoe leveled by the present method, when removed from the last, has a substantially 70 flat interior surface on the insole. The ridge which theoretically would be formed by the groove 14 is of barely sufficient prominence to be evident to the sight or to the touch. The outwardly curved portion of the margin of the insole is outside the area of contact of the foot with the insole, and this formation of the margin tends materially to prevent the margin of the insole from curling upwardly 75 and causing discomfort to the foot, as it occasionally does in welt shoes made on the usual last. The method of leveling a shoe disclosed above is not claimed herein since it is claimed in my copending divisional application Serial No. 431,800 filed Feb. 27, 1930. 80

Having thus described my invention, what I claim as new and desire to secure by Letters Patent of the United States is:

1. A last for shoes having in the margin of its bottom surface a shallow groove one side of the groove sloping inwardly and toward the body of the last from the extreme edge of the last bottom and extending from the breast line on one side of the shank along the shank to the forepart and along the shank to the breast line on the other side. 110

2. A last for shoes having a groove extending about the periphery of the forepart, the groove sloping from the edge of the last bottom inwardly and toward the body of the last and being deepest along a line located beneath the inseam of a shoe placed upon the last. 115

3. A last for shoes having the margin of the forepart inclined inwardly and toward the body of the last to cause the leveling pressure to force the inseam inwardly, the central portion of the last bottom having the usual formation. 120

4. A last for welt shoes having the forepart formed to concentrate the leveling pressure along a line at the extreme edge of the insole and to relieve pressure on the inseam.
5. A last for welt shoes having the forepart formed to concentrate the leveling pressure along a line at the extreme edge of the insole and to relieve pressure on the inseam, the shank portion of the last having a recess to receive the shank portion of the insole.

10 In testimony whereof I have signed my name to this specification.

CLARENCE I. LANDER.
